UNITED STATES PATENT OFFICE.

FRANK J. MACDONALD, OF ELLET, OHIO, ASSIGNOR TO THE B. F. GOODRICH COMPANY
OF NEW YORK, N. Y., A CORPORATION OF NEW YORK.

METHOD AND APPARATUS FOR FORMING SHOE LININGS OR THE LIKE.

Application filed June 17, 1926. Serial No. 116,561.

This invention relates to methods and apparatus for manipulating sheet material, as in joining the margins of a shoe-lining blank to form a conoidal lining, and its objects 5 are to provide accurate and economical procedure and apparatus for performing such work.

Cross-reference is hereby made to my co-pending applications Serial No. 703,905, filed 10 April 3, 1924, Serial No. 704,502, filed April 5, 1924, and Serial No. 11,525, filed February 25, 1925, which have relation to some of the subject matter disclosed herein.

Of the accompanying drawings:
15 Fig. 1 is a side elevation of a machine embodying and adapted to carry out my invention in its preferred form.

Fig. 2 is a rear elevation of the same with parts sectioned and broken away.

20 Fig. 3 is a plan view of the machine with parts broken away.

Fig. 4 is a perspective view of parts of a tape-applying and severing device.

25 Fig. 5 is a horizontal section on line 5—5 of Fig. 2.

Fig. 6 is a perspective view of the finished work.

Fig. 7 is a perspective view of a lining-manipulating unit.

30 Fig. 8 is a face view of one of the lining blanks upon which the machine operates.

Fig. 9 is a section on line 9—9 of Fig. 5.

Fig. 10 is a section on line 10—10 of Fig. 5.

35 Fig. 11 is a section on line 11—11 of Fig. 3 with the lining-manipulating jaws in open and projected position.

Fig. 12 is a similar section with the lining-manipulating jaws in closed or retracted position.

40 Fig. 13 is a diagrammatic view of parts of the seaming mechanism.

Fig. 14 is a similar view of the same at a different stage of operation.

45 Fig. 15 is a front view, with parts in section, of instrumentalities for overlapping and joining the heel margins of the lining.

General description.

50 The machine comprises a hinged, drop-away support for receiving the lining; a pair of suckers adapted to be positioned at the outer end of the support to receive and anchor the respective heel margins of the lining when the latter is slid upon the support

so that its heel margins project over the suckers; respective sets of nipper jaws adapted to engage the heel margins of the lining as it rests upon the support and to draw its margins over the suckers; abutment members 60 adapted to stop the lining at the desired position in this drawing movement, the nippers thereafter sliding upon the lining in their further movement; means for causing the support to drop and the nipper-jaw assemblies 65 to swing out of the way after the suckers have engaged the heel margins of the lining; means for then so moving the suckers as to bring the said heel margins into over-lapped relation; and means for applying 70 a tape adhesively to the over-lapped margins and to press the tape and the margins together to form the vertical heel-seam of the lining.

General driving mechanism.

75 Referring to the drawings, the machine comprises a frame 10 in which is journaled a cam shaft 11 having driving means by which it is adapted to be driven through one 80 revolution to effect each cycle of operations and then automatically to be stopped. The said driving means comprises a gear 12 secured upon the shaft 11 and meshed with a gear 13 secured upon a hollow shaft or 85 quill 14 journaled in the frame and formed at its other end as a jaw-clutch member 15 and also formed with a brake drum 16 at an intermediate part. A clutch member 17 adapted to coact with the clutch member 15 90 is slidably keyed upon a shaft 18 which is journaled in the quill 14 and in the frame and is provided with a drive pulley 19 having a belt 20.

95 For engaging and disengaging the clutch members a three-armed lever is secured upon a shaft 21 journaled in a floor-bracket 22, the said lever having a forked arm 23, constituting a shipper arm for the clutch member 17, a brake arm 24 formed with a brake shoe 25 adapted to coact with the brake drum 16 to stop the machine when the clutch member 17 is disengaged, and a latch-arm 26 adapted to receive under it and be supported by a latch-arm 27, to hold the clutch engaged 105 and the brake arm clear, upon the throwing in of the clutch, for which purpose a foot lever 28 is secured to the shaft 21, the latch-arm 27 being formed integrally with an emergency-stopping foot-lever 29 which is 110

secured upon a shaft 30 journaled in the floor-bracket 22 and provided at its other end with a cam arm 31 which is adapted to be engaged at the end of each cycle of operations by a cam 32 formed on a cam drum 33 upon the shaft 11. For yieldingly urging the latch-arm 27 toward latching position, the cam lever 31 is connected with the base of the machine by a pull spring 34.

10 *Lining support.*

The frame 10 includes a bed-plate 35, from one end of which rises a pair of brackets 36, 36 between the ends of which is hinged a lining-support 37, by means of trunnions 38, 38 journaled in the brackets. One of the trunnions 38 has secured thereon a rocker arm 39 connected by an adjustable link 40 with one arm 41 of a cam lever 20 fulcrumed upon a shaft 42 mounted in the frame of the machine. The arm 41 to which the link 40 is connected is also connected by a pull spring 43 with a stationary bracket 44, Fig. 1, the spring 43 being 25 adapted to urge the lining-support 37 toward its horizontal, lining-receiving position, and the cam lever arm 41 being adapted to swing the lining-support 37 downward, against the force of the spring 43, to clear 30 it from the lining after the latter has been engaged by the suckers. Formed integrally with the lever arm 41 is a lever arm 45 provided at its swinging end with a cam roller 46 running upon a cam disk 47 secured upon the shaft 11.

35 *Margin-engaging sucker mechanism.*

The margin-engaging suckers are shown at 48, 49 and are adapted to be presented to 40 the outer end of the lining-support 37 as shown in Fig. 3, each having an arched, upwardly-facing suction surface such as the apertured surface 49^a shown clearly in Fig. 7. Each of the suckers is formed upon the 45 upper end of a hollow crooked arm 50 formed at its lower end with apertures 51, 51 through a portion of its wall lying within a suction cavity 52 formed in a suction block 53 in which the two hollow arms 50 are journaled with an air-tight fit (Fig. 15), each arm 50 being formed with an offset journal portion mounted in the suction-block 53 and held downward therein by a tongue spring 54 secured to the suction block 53 at 55 (Fig. 10) and bearing upon a rounded projection 56 formed on the arm 50 at its axis, to urge the arm downward in its bearing.

Each of the suckers 48, 49 is offset from its 60 arm 50 (see Fig. 7) and its end portion most remote from the arm 50 is formed with a downwardly-projecting stud 57 which is coaxial with the journal portion of the arm 50 which is mounted in the suction box 53, the stud 57 extending into a journal aperture 65 formed in a plate 58 (Figs. 1, 3 and 15),

which projects from the top of a vertical bracket 59 rising from the bed-plate 35, the offset form of the arms 50 with relation to their journal and sucker portions being such as to permit the suckers to be swung from 70 their lining-receiving positions of Fig. 3 to their margin-joining positions over the plate 58, as shown in Fig. 15.

For so swinging the suckers the journal portion of each arm 50, below the suction block 53, has secured thereto a rocker arm 60 connected by a pull spring 61 with a pin 62 projecting downward from the bed-plate 35, the springs 61 being adapted to urge the arms 50 of the suckers against upstanding lugs 62^a rising from the bed-plate 35, said lugs determining the normal or lining-receiving positions of the suckers, and the rocker arm 60 being adapted to be engaged by respective cams 63, 63 formed upon a cam drum 64 (Figs. 2 and 5) on the shaft 11 to swing the suckers to their margin-seaming positions of Fig. 15. A cam 65 formed upon the drum 64 is adapted to engage the lower end of the arm 50 of the sucker 48, as shown in Fig. 15, to lift the sucker 48 as it approaches the sucker 49, for overlapping the margins of the lining as there shown.

For applying and breaking the suction of the suckers at proper times the suction block 53 communicates, through a hose 67, with an ejector 66 actuated by pressure fluid supplied through a pipe 68 provided with a stop-valve 69 having an operating lever 70, the latter being connected by a link 71 with one arm 72 of a cam lever fulcrumed on the frame at 73, the other arm 74 of the cam lever being formed with a cam face adapted to be engaged once during each cycle by a cam 75 formed upon a cam drum 76 on the shaft 11, and the arm 72 being connected by a pull spring 77 with the machine frame.

110 *Lining-positioning mechanism.*

The means for drawing the lining on the support 37 to bring the heel margins thereof to the proper positions over the suckers 48, 49 comprises a pair of jaw-carrying arms 78, 78 secured to the upper ends of respective hollow shafts 79, 79 which are journaled in brackets 80, 80 rising from the bed-plate 35. The arms 78 being adapted to be swung into positions just in the rear of the respective suckers 48, 49 when the latter are in lining-receiving position. Each arm 78 is formed with a vertical face 81 (Fig. 7) adapted to be abutted by the edge of the shoe-lining, shown at 82, to position the margin of the lining over the adjacent sucker when the said margin is drawn against the vertical stop-face 81 of the arm 78 by a set of nipper jaws comprising upper jaws 83, 83 and lower jaws 84, 84 which are 115 120 125 130

adapted to be projected and retracted through slots 85, 85 formed in an upstanding flange portion of the arm 78.

The lower jaws 84 of the several pairs on each of the arms 78 are formed integrally with a sliding arm 86 which is hinged on a shaft 87 journaled in a rocking frame 88, the frame 88 being secured upon a shaft 89 which is journaled in bearings 90, 90 formed upon the arm 78, and the shaft 89 has secured to the end thereof adjacent the arm's vertical hinge shaft 79 a rocker arm 91 provided at its outer end with a contact plate 92 adapted to be engaged by a vertical push-rod 93 slidably mounted in the hollow shaft 79, the push rod being adapted to swing the rocking frame 88 away from the sucker, against the force of a pull spring 94 connecting the shaft 87 with the arm 78, to retract the nipper jaws 83, 84 past the stop-face 81 of the bracket, and thus to draw the shoe lining 82 against the said stop-face all along its heel margin, the jaws 83, 84 being adapted to slide upon the lining in their further retractive movement after the lining has been stopped against the face 81.

For causing the nipper jaws to stand open with the upper jaws 83 raised, when the nipper jaws are in their projected positions, and to close and bear yieldingly upon the lining as the jaws are retracted past the stop-face 81, a small cam roller 95 (Figs. 7, 11 and 12), is adapted to run upon the upper face of each one of the upper jaws 83, each of the said cam rollers being journaled in the bifurcated outer end of a small lever 96 which is pivoted at 97 in the adjacent slot 85 of the upstanding flange portion of the arm 78, and a pull spring 98 connects an intermediate part of the arm 96 with a plate 99 secured to the arm 78 to cause the roller 95 to bear yieldingly upon the jaw 83.

The several upper jaws 83 of each of the two sets are pivoted upon a curved rod 100 which lies in a curved channel rising from the sliding frame 86, the ends of the rod 100 being secured to the rocking frame 86 as by being riveted as shown clearly at 102, 102 in Fig. 7, the walls of the channel being notched to admit the hub portions of the upper jaws 83 and to provide spacing blocks 103, 103 between the adjacent jaws. Each of the upper jaws 83 is formed with an upstanding projection or cam 104 at the rear of its pivot 100, the said projection being adapted to be abutted by the cam roller 95, at the limit of the projective movement of the sliding jaw-carrying frame 86, to cause the jaws to open. The lower jaws 84 are adapted to slide upon the lower end walls of the slots 85 and upon the sucker 48 or 49 to support the frame 86 as the said frame is projected and retracted, and the said lower jaws are formed with rounded lower faces 105 at their forward ends to cause them to

ride up over the sucker in their projective movement as will be clear upon reference to Fig. 12.

For swinging the jaw-carrying arms 78 to the lining-receiving positions of Fig. 3 and 70 to inoperative positions clear of the work-manipulating station, each of the hollow shafts 79 has secured to its lower end a cam arm 106 urged toward lining-receiving position by a pull-spring 107 connecting it with the frame, the arm 106 being provided with a stop-screw 108 adapted to abut a lug 109 projecting downward from the bed-plate 35 to position the jaws to receive the shoe-lining, and the arm 106 being provided at its swinging end with a cam stud 110 adapted to be engaged by a cam 111 formed on the cam drum 76 (or 33) to swing the jaw-carrying arm to inoperative position. For raising and lowering the slide-rods 93 to project and retract the jaw-carrying slide frames 86, the lower ends of the said slide rods rest upon the free ends of cam arms 112, 112 which are journaled on the shaft 42, said arms serving to take the tangential thrust of respective cams 113, 113 formed on the cam drums 76 and 33 and to be lifted by said cams to actuate the slide rods 93.

Seam-tape-applying mechanism.

A reel 116 (Figs. 1, 2 and 3) for supplying a heel-seam tape 117 is journaled upon a vertical axis upon a spindle 118 rising from the bed-plate 35, and rollers 119, 120, 121, 122 and 123 are journaled upon fixed parts of the framing and are adapted to guide the strip 117 to the upper end of a cam-actuated, upstanding, tape-applying frame or arm 125 of which the upper end portion consists of a pair of hooked side plates 125^a, 125^a having secured between them near their outer ends a block 126 adapted to coact with a pawl 127 to hold the tape 117 against recession with relation to the arms 125, the pawl 127 being formed with pivot studs 128, 128 (Figs. 1 and 3) projecting into respective slots such as the slot 129 formed in the side plates 125^a of the arm, so that the pawl will be drawn forward by the tape 117 to the extent permitted by the slots 129 in the relative forward movement of the tape and will permit only a limited recession of the tape, the studs 128 running in the slots 129 when the relative forward pull upon the tape is released, by the severing of the portion of the tape which has been applied to the heel seam of a lining.

Means hereinafter described is provided for causing the curved, over-hanging, upper end portion of the arm 125, which carries the pawl 127 and block 126, to rise and move forward to carry the leading end of the tape 117 to the forward end of the heel seam of the upper, then to descend to attach the

4

leading end of the tape to the upper, and then to retract along the heel seam to apply the tape thereto, and a seam-pressing roller 130 is journaled between the outer ends of the side plates 125^a in position to roll the tape onto the heel seam during such rearward movement of the arm 125.

The roller 122 (see Fig. 1) is so positioned with relation to the rollers 122 and 123 as to lie within a loop of the tape 117 and to act as a take-off roll to feed the tape from the reel 116 to the tape-applying arm 125, but only when the tape is tightened by the forward movement of the arm, the roll slipping within the loop at other times, the said roller 122 being secured upon a drive shaft 131 having constant-drive connection with the shaft 11 through gears 132, 133, a shaft 134 and a sprocket chain 135 (see Figs. 2 and 3).

The tape-applying arm or frame 125 is connected to the frame of the machine by a pull spring 126 (Fig. 1) and is fulcrumed at 127 to the outer end of a yoke or frame 128 of which the other end is hinged upon the shaft 42, one arm of the frame 128 being provided with a cam lug 137 adapted to be engaged once during each revolution of the cam drum 64 by a cam 138 mounted upon the said drum, and one arm of the frame 125 is formed with an extension 139 projecting downward beyond its hinge connection 127 with the frames 128, the said extension being provided at its lower end with a cam roller 140 adapted constantly to run upon a cam disk 141 secured upon the shaft 11, the cam 138 and the cam disk 141 being adapted to cause the frame 125 to go through a cycle of movements illustrated in Figs. 13 and 14, in which its upper, tape-applying end rises and moves forward over the suckers 48, 49 without contact with the work thereon, to carry the leading end of the tape to the forward end of the heel seam, then descends to apply the leading end of the tape to the heel seam, and then moves backward along the heel seam to lay the tape thereon and to cause the roller 130 to press it in place.

For severing the tape at the adjacent end of the heel seam after each seaming operation, a shear plate 151 is mounted upon a bracket 152 (Figs. 1 and 4) which is pivoted at 153 (Fig. 1) upon the upstanding bracket 59 and adapted to be held in adjusted positions about its pivot by an adjustable link 154 connecting an intermediate part of the bracket 152 with a lower part of the bracket 59. For coacting with the shear plate 151 to sever the tape 117, a shear blade 155 (Figs. 1 and 4) is secured to a small rock shaft 156 journaled in the bracket 152 and provided at its opposite end with a thrust spring 157, an adjusting nut 158, and a bifurcated rocker arm 168 (Fig. 4), the rocker arm 168 being

adapted to be swung upward and downward by a stud 169 projecting between its two forks from a vertical slide-rod 170 which is mounted in slide bearings 171, 172 projecting from the bracket 152. The lower end of the slide-rod 170 is connected by an adjustable link 173 with one arm 174 (Figs. 5 and 10) of a two-armed cam lever which is fulcrumed at 175 between the arms of a forked bracket 176 projecting downward from the bed-plate 35, the other arm 177 of the said lever projecting into the path of a cam dog 178, mounted upon the cam drum 64, the said dog being adapted through the lever arms 177, 174 and link 173 to lift the slide-rod 170 once during the revolution of the drum and thus to actuate the shear blade 155, the slide-rod structure being adapted to descend of its own weight to lift the blade and being stopped in its descent by a lug 179, (Fig. 10) striking a lug 180 on the bracket 176.

Operation.

In the operation of the machines, the parts being in the positions shown in Figs. 1, 2 and 3, a shoe-lining 82 is symmetrically mounted upon the support 37, its heel margin on the side of the sucker 48 being folded back as shown at 200 in Fig. 11, and the lining is shoved on the support towards the suckers 48, 49 so that its heel margins enter between the nipper jaws 83, 84, which are standing open as shown in Fig. 11.

The foot lever 28 is then depressed, which throws in the clutch member 17, whereupon the latching arm 27, impelled by the spring 34, passes under the latching arm 26 and latches the clutch in engagement for a cycle of operations, the shaft 11 thus being caused to rotate in a clockwise direction as viewed in Fig. 1. The jaws 83, 84 are caused to close lightly upon the heel margins of the lining and to be retracted with relation to the abutment face 81 of the jaw-carrying arm 78 (see Fig. 7), to draw the heel margins against the said abutment face of each arm throughout the entire lengths of the said margins and thus accurately to position the said margins over the suckers 48, 49, the retractive movement of the jaws being effected through the action of the cams 113, push rods 93, and rocker arms 91, and the closing movement of the jaws being effected through the action of the springs 98 (see Fig. 11), causing the rollers 95 to bear yieldingly upon the upper jaws 83, 84 as they run upon the jaws, relatively, from the latters' pivots toward their larger ends.

Shortly before the jaws slip from the extremities of the margins, suction is applied to the suckers 48, 49 through the action of the cam 75, lever arms 74 and 72, link 71 and valve lever 70, so that as the margins are released by the jaws while held accurately

abutted throughout their extent against the stop faces 81, they are drawn against the faces of the suckers and there held by suction.

5 Next the jaw-carrying arms 78 are swung away from the work-manipulating position, through the action of the cams 111, levers 106 and hollow shafts 79. At the same time the lining support 37 is caused to swing down-
10 ward and leave the lining suspended from the suckers, through the action of the cam 47 and lever arms 45 and 41 and link 40 (see Figs. 1, 2 and 9). The suckers 48, 49 are then swung from their lining-receiving po-
15 sitions of Fig. 3 to their seaming positions of Fig. 15, through the action of the cams 63 and arms 60 (see Figs. 5, 10 and 15), the sucker 48, whose lining margin has been folded back as above-described being mean-
20 while slightly lifted by the action of the cam 65 (Fig. 15), so that the said margin, spring-
ing back to a substantially straightened con-
dition projects over the other heel margin of the lining, as shown clearly in Fig. 15,
25 when the two suckers are brought together as there shown. The cam 65 then passing from under the journal portion of the arm 50 of the sucker 49, permits the spring 54 of the latter, as well as its own weight, to
30 cause the sucker 49 to descend sufficiently to bring the two margins of the lining into contact with each other.

The tape-applying arm 125 is then caused to rise and move forward at its upper end so that the leading end of the tape 117 is carried to the forward end of the heel seam of the lining, the arm then descending, so that the leading end of the tape is applied to the seam, and the upper end of the arm 40 then runs back along the heel seam, laying the tape thereon and causing the roller 130 to press it in place under the yielding force of the spring 126, these movements being effected through the action of the cam 138 and cam lug 137 of the frame 128 and through the action of the cam disk 141 and cam roller 140 (see Figs. 2 and 14).

During the forward movement of the tape-applying arm 125, its tightening of the tape 117 causes the latter to grip the feed roll 123, so that the latter feeds the tape from the reel 116 and permits it to be drawn forward by the arm 125 without excessive strain, the tape then releasing its grip upon the roller 123 so as not to be driven thereby, in the return movement of the arm 125.

When the tape-applying arm 125 has thus returned to its starting position, the tape will overlie the shear plate 151 (Fig. 4), and the tape is then severed at the edge of the shear plate, which is closely adjacent the end of the heel seam of the lining, by the blade 155, which is operated through the action of the cam dog 178, lever arms 177, 174 (see Fig. 10), the link 173 and the push

rod 170, the blade 155 being then lifted by the preponderance of weight in the parts mentioned, when the cam dog 178 has cleared the lever arm 177.

After the severing operation, the passage 70 of the cam 75 permits a spring 77 to function to break the vacuum in the suckers and the seamed lining is removed from the suckers by hand.

Then the passage of the cams 63 permit 75 the springs 61 to return the suckers to lining-receiving position, the further rotation of the cam disc 47 permits the spring 43 to return the lining-support 37 to lining-receiving position, and the passage of the cams 111 80 permits the springs 107 to return the jaw-carrying arms 78 to lining-receiving position, after which passage of the cams 113 permits the springs 94 to project the jaws through the slots 85, over the suckers, the 85 rollers 95 engaging the projection 104 of the upper jaws at the limit of this projective movement and thus to open the jaws and hold them open in lining-receiving position, to receive the next lining, as shown in 90 Fig. 11.

The cycle of operations thus being completed, the machine is automatically stopped by the cam 32 striking the lever 31 and forcing the latching arm 27 from under the 95 latching arm 26, whereupon the spring 32 retracts to throw out the clutch member 17 and concurrently to apply the brake shoe 25 to the brake drum 16.

The cycle of operations as described is 100 then repeated.

My invention is susceptible to extensive modification within its scope, and I do not wholly limit my claims to the exact procedure or construction hereunder described. 105

I claim:

1. The method of joining two margins of sheet material which comprises holding one of the margins by suction applied thereto at a distance back from its edge and while so holding it overlapping it upon the other margin with the said other margin on that side of the first margin to which the suction is applied. 110

2. The method of forming a conoidal 115 structure of sheet material which comprises holding two margins of a blank of the material by suction and while so holding them bringing them together in overlapped relation to each other. 120

3. The method of forming a conoidal structure of sheet material which comprises bringing two margins of the material together by engagement with one face only of each margin and applying a seam strip to the two margins while such engagement is continued. 125

4. The method of forming a conoidal shoe lining which comprises supporting a U-shaped blank of lining material in a 130

spread condition in a determinate position and by determinate relative movement of its two heel margins bringing the said margins into overlapped relation.

5. A method as defined in claim 4 in which the two margins are positioned against an abutment and are then engaged by one face only as so positioned and are brought into overlapped relation by such engagement.

10. Apparatus for joining two margins of sheet material, the said apparatus comprising a pair of anchoring members each adapted to hold one of the margins by engagement with only one face thereof with the 15 two margins in substantially the same plane and means for relatively turning the said members, about axes approximately normal to said plane, into side-by-side relation with their margin-engaging portions facing in 20 the same direction.

25. 7. Apparatus for joining two margins of sheet material, the said apparatus comprising a pair of suckers adapted to engage the respective margins in determinate margin-receiving positions and means for effecting 30 determinate relative movement of the suckers to bring the margins into overlapped relation.

35. 8. Apparatus for joining two margins of sheet material, the said apparatus comprising a pair of margin-engaging members pivoted to swing about parallel axes approximately normal to their margin-engaging faces and each adapted to hold one of 40 the margins by engagement with only one face thereof.

45. 9. Apparatus for joining two margins of sheet material, the said apparatus comprising a pair of anchoring members each adapted to hold one of the margins by engagement with only one face thereof, means for effecting relative movement of the said members to bring the margins into overlapped relation, and means for applying a seam strip to the said margins in their overlapped relation.

50. 10. Apparatus for joining two margins of sheet material, the said apparatus comprising means for bringing the two margins together in determinate relation by determinate relative movement and means for then progressively applying a seaming strip to the said margins while they are held in such relation.

55. 11. Apparatus for joining two margins of sheet material, the said apparatus comprising a pair of suckers adapted to engage the respective margins, means for drawing the margins to determinate positions with relation to said suckers, and means for moving the suckers to present one of the margins to the other.

60. 12. Apparatus for joining two margins of sheet material, the said apparatus comprising a pair of margin-anchoring members,

abutment members adjacent the respective margin-anchoring members and adapted to be abutted by edges of the sheet material to position the latter, means for drawing the margins of the sheet material against the 70 said abutment members, and means for moving the margin-anchoring members to present one of the margins to the other in seaming relation.

75. 13. Apparatus as defined in claim 12 in which the margin-drawing means comprises a member adapted to slide upon the margin in a continuation of its movement after it has drawn the margin against the abutment member.

80. 14. Apparatus for joining two margins of sheet material, the said apparatus comprising a drop-away support for the sheet material, a pair of pivoted, hollow arms formed with respective margin-engaging suckers on 85 their outer ends, and adapted to be turned on their pivots to positions such that the suckers are in proximity to the said support and to other positions such that margins respectively anchored by the suckers are presented to each other, means for drawing sheet material upon the said support to a determinate position with relation to the suckers, and means for applying a seam strip to the margins when the latter are presented to 90 each other.

95. 15. Apparatus as described in claim 14 including actuating mechanism adapted upon being set in motion to actuate all of the defined instrumentalities in timed relation 100 throughout, and automatically to stop them at the end of, a cycle of operations in which they automatically effect the margin-joining operation and are returned to their starting positions.

105. 16. Sheet-manipulating apparatus comprising a sucker, an abutment member adjacent thereto, and a pair of jaws adapted to draw a margin of the sheet into a position in which it overlies the sucker with its edge 110 against the abutment member.

115. 17. Sheet-manipulating apparatus as defined in claim 16 including yielding means for holding the jaws closed upon the sheet, the jaws being mounted for retractive movement past the abutment member and adapted to slide upon the sheet in their further movement after the sheet has been stopped by contact with the abutment member.

120. 18. Sheet-manipulating apparatus comprising a drop-away support for the sheet and a sucker mounted to be positionable adjacent the support and adapted to engage a margin of the sheet projecting beyond the 125 sheet-contacting surface of the support.

125. 19. Sheet-manipulating apparatus comprising a pair of elongated suckers pivoted upon adjacent, substantially parallel axes and adapted to be turned from sheet-receiv-

ing positions to positions in which their suction faces are closely adjacent and substantially parallel to each other, to bring respective margins of sheet material held thereby into seaming relation, the pivotal axes of the said suckers being approximately normal to their sheet-engaging faces.

20. Sheet-manipulating apparatus as defined in claim 19 in which the suckers are mounted for relative movement such as to overlap a sheet margin held by one with relation to a sheet margin held by the other.

21. The combination of stationary means for supporting sheet material and means for applying a strip of material thereto, the strip-applying means comprising a strip-drawing member, means on said member for guiding and for preventing relative recession of the strip, and means for moving the said member forward along the sheet without engagement with the work and for then moving it backward along the sheet while urging it yieldingly toward the work.

22. The combination of stationary means for supporting a piece of sheet material, means for giving off a strip of material progressively to sheet material on said supporting means, the last said means comprising a strip-drawing member, means on said member for guiding and preventing relative recession of the strip, means for moving the said member forward without engagement with the work and for then moving it in the reverse direction while urging it yieldingly toward the work, and means for feeding the strip to the said member during its forward movement only.

23. A combination as defined in claim 22 in which the strip-feeding means comprises a drive-roller embraced by a loop of the strip and adapted to drive the latter only when the strip is tightened by the forward movement of the strip-drawing member.

24. Apparatus for joining two margins of sheet material, the said apparatus comprising means for presenting the margins to each other at a seaming position by determinate movements, means for progressively

laying a seam strip on said margins as so presented, and means mounted adjacent the seaming position for severing the strip at a determinate position with relation to the said margins.

25. Apparatus as defined in claim 24 including mechanically timed actuating means for effecting cyclic operations of the several instrumentalities defined.

26. Apparatus for joining two margins of sheet material, said apparatus comprising a pair of anchoring members each adapted to hold one of the margins and the two being adapted to receive the margins approximately in the same plane and means for effecting such movement of one of the said members with relation to the other as to turn one of the margins approximately in its own plane and thereby to present it to the other margin in seaming relation thereto.

27. Apparatus for joining two margins of sheet material, said apparatus comprising a pair of anchoring members each adapted to hold one of the margins by engagement with only one face thereof and the two being adapted to receive the margins approximately in the same plane and means for effecting such movement of one of the said members with relation to the other as to turn one of the margins approximately in its own plane and thereby to present it to the other margin in seaming relation thereto.

28. Apparatus for joining two margins of sheet material, said apparatus comprising a pair of anchoring members each adapted to hold one of the margins and the two being adapted to receive the margins approximately in the same plane and means for effecting such movement of one of the said members with relation to the other as to turn one of the margins approximately in its own plane and thereby to present it to the other margin in seaming relation thereto and means for pressing the said margins together to form a seam.

In witness whereof I have hereunto set my hand this 11th day of June, 1926.

FRANK J. MacDONALD.
